UNITED STATES PATENT OFFICE.

GEORGE B. STRYKER, OF WILSON, NORTH CAROLINA, ASSIGNOR TO KWICK-BATH MANUFACTURING CORPORATION, OF WILSON, NORTH CAROLINA, A CORPORATION OF NORTH CAROLINA.

BATH-CABINET.

1,277,502.

Specification of Letters Patent. Patented Sept. 3, 1918.

Application filed September 7, 1917. Serial No. 190,167.

To all whom it may concern:

Be it known that I, GEORGE B. STRYKER, a citizen of the United States, residing at Wilson, in the county of Wilson and State of 5 North Carolina, have invented certain new and useful Improvements in Bath-Cabinets, of which the following is a specification.

The present invention relates to bath-cabinets and consists in the combinations and 10 arrangements of parts hereinafter described and particularly set forth in the accompanying claims.

The invention has for its purpose to provide a portable bath-cabinet for household 15 use which comprises a bath tub, a water supply tank therefor, means for heating the water, a closet, and medicine cabinet, all mounted on a suitable supporting structure and so arranged that the bath tub may be 20 easily raised from its position on the floor to house the other apparatus, and having a curtain closure adapted to completely conceal the aforesaid apparatus and be readily moved from position when its use is desired.

25 A further purpose of the invention is to provide a bath-cabinet of the above mentioned type which is of simple and inexpensive construction, and arranged in a compact manner to the end of being readily accessible, 30 and economical of space, and one wherein no particular or special knowledge is required for its use.

The bath-cabinet is intended primarily for the use of those whose homes are located in 35 outlying districts or elsewhere, where the conveniences of the modern bath-room are not available or where there is no water or gas main supply.

The invention is shown by way of illustration 40 in the accompanying drawings, wherein:

Figure 1 is a front elevational view of the bath-cabinet complete,

Fig. 2 a side elevational view thereof showing the bath-cabinet in lowered position,

Fig. 3 a central sectional view of the water tank taken on the line 3—3 of Fig. 1,

Fig. 4 a horizontal sectional view on the line 4—4 of Fig. 1 of the water tank showing the heat coil,

Fig. 5 a similar view on the line 5—5 showing the heater,

Fig. 6 a detail view of the water drain feature,

Fig. 7 a transverse sectional view thereof 55 taken on the line 7—7 of Fig. 6, and

Fig. 8 a detail perspective view of one of the heater supporting brackets.

Referring to the construction in further detail, 1 designates a suitable supporting 60 structure adapted to be set against the wall in any convenient position in the room, and said structure is separated into compartments 2 and 3. A medicine cabinet 4 is located in the compartment 3 at the upper end, 65 and a towel rack 5, or other suitable device, is located just below said cabinet.

A box seat structure 6 is located at the base of the cabinet compartment 3 in the manner clearly shown in Fig. 1. 70

A pair of brackets 7 is secured to the supporting structure at the lower end of the compartment 2 and supports the trunnions 8 of the bath tub 9 that is adapted to be swung into either of the positions shown and 75 indicated in Fig. 2, as will be understood. The tub 9 has an outlet pipe 10 adapted to enter the drain pipe 11 located within and below the floor 12 of the room wherein the cabinet is mounted. Said floor 12 is cut 80 away, as at 13, to receive a sliding piece 14 that is normally held to close the drain pipe 11, by the retraction spring 15 (see Fig. 7). The sliding piece is adapted to be moved to uncover the drain by an upwardly projecting 85 part 16 that is engaged to be moved by the outlet pipe 10 of the tub 9 as indicated by the arrow.

An arm 17 is secured to the rear end of the tub 9 and supports a weight 18 to counterbalance the tub on the trunnions 8 and thereby render the same easy of manipulation as will be understood. The tub is further provided with a pair of lifting weights 19 mounted to operate within the boxings 20, 95 and connected to the tub on opposite sides by the cords or chains 21 that travel on the groove pulleys 22 journaled in said boxings as shown. By the travel of the three weights (18 and 19) the tub may be readily lifted 100 into an upright position when the entire cabinet is concealed by the curtain 23 slidably supported on the bracket arm 24.

A water supply tank 25 is mounted above the tub 9 and secured to the back of the 105 cabinet by any suitable fastening means. Said tank is divided into a hot water chamber 26 and a cold water chamber 27 by the

spaced partitioning walls 28, and the side walls of the tank, between said partitions are provided with apertures 29 to admit air for giving the necessary insulation between 5 the hot and cold water chambers.

A faucet 30 communicates with the cold water chamber 27 by the pipe 31, and a similar faucet 32 communicates with the hot water chamber 26 through the pipe coil 10 33 located immediately beneath the bottom wall 34 of the water tank as shown in Figs. 3 and 4.

The hot water chamber is adapted to be heated by an oil burner apparatus consisting 15 of a frame 35 swingingly mounted on the pin 36 of the bracket arm 37 as shown in Fig. 5. A lug 38 secured to the frame 35 is adapted to engage with the spring catch 39 of the bracket arm 40, and hold the frame 35 20 in rigid position.

An oil tank 40^a is suitably mounted in the frame 35 and connects with the usual form of burners 41 by the pipe 42, and an opening 43 in the front of the frame 35 gives ready 25 access for regulating the burners.

It is obvious that those skilled in the art may vary the details of construction and arrangement of parts without departing from the spirit of my invention, and therefore I do

not wish to be limited to such features except 30 as may be required by the claims.

Having thus described my invention, what I claim as new and desire to secure by U. S. Letters Patent, is:

1. In a bath-cabinet the combination of a 35 supporting structure, a bath tub swingingly mounted in said structure, and having a downwardly projecting outlet pipe, a drain pipe located beneath the bath tub, a slidable closure for said drain pipe adapted to be uncovered by said outlet pipe, and a curtain closure for the bath-cabinet, substantially as 40 set forth.

2. In a bath-cabinet the combination of a 45 supporting structure, a bath tub mounted in said structure, a water supply tank located above the bath tub, a pair of bracket arms mounted on said structure below the water tank, a frame swingingly mounted on one of said bracket arms and adapted to have locking engagement with the other bracket arm, and an oil burner apparatus mounted on said swinging frame adapted for heating water in the tank, and a closure for the bath-cabinet, substantially as set forth.

55 In testimony whereof I affix my signature.

GEORGE B. STRYKER.
